UNITED STATES PATENT OFFICE.

WALTER P. MURPHY, OF CHICAGO, ILLINOIS.

CAR END BRACE.

1,152,201.

Specification of Letters Patent. Patented Aug. 31, 1915.

Application filed November 5, 1914. Serial No. 870,488.

To all whom it may concern:

Be it known that I, WALTER P. MURPHY, a citizen of the United States, and a resident of the city of Chicago, in the county of Cook and State of Illinois, have invented a new and useful Improvement in Car End Braces, of which the following is a specification.

This invention relates to the end framing 10 of wooden box cars, and particularly to means for repairing damaged cars and for strengthening old style cars to fit them for present day service conditions.

The principal object of the invention is a 15 metal frame construction for attachment to the end of a wooden car outside the sheathing to keep it from being knocked out by shifting lading.

A further object of the invention is an 20 arrangement of parts which can be readily applied to cars already built, and which will cooperate with the car side and end framing to prevent distortion thereof and to stiffen the roof.

25 The invention consists in a metal frame for attachment to the end of a car for the purposes above set forth, and in the parts and arrangements hereinafter described and claimed.

30 The accompanying drawings illustrate an embodiment of the invention applied to a wooden car of ordinary construction.

In the drawings, in which the same reference characters designate like parts in the 35 several views, Figure 1 is an end elevation of the car showing the car framing in dotted lines; Fig. 2 is a plan view of the same, the roof being removed; Fig. 3 is a longitudinal section of the same on the center line 40 of the car; Fig. 4 is a bottom view of the middle portion of the end sill and parts of the car frame associated therewith, partly in section; and Fig. 5 is a longitudinal section of the lower portion of the end of the 45 car, showing the end sill and frame connections, on the line 5—5 in Fig. 4.

50 Referring to the drawings, the car illustrated therein comprises a wood end sill 11, and center and side sills 12 and 13 supporting the flooring 14. The end sill is bolted to the car body bolster by means of a center tie rod 15, and truss rods 16 extend from one end sill to the other and tie them together.

55 The end plate 17 and side plates 18 are supported by means of corner posts 19 and side and end posts 20 and 21 which have

their lower ends secured to the side and end sills, respectively. Diagonal side corner braces 22 extend from the ends of the end sill to the side plates at the tops of the 60 first pair of side posts 20, and diagonal end corner braces 23 extend from the ends of the end sill to the end plate at the tops of the end posts 21. The side sheathing boards 24 and end sheathing boards 25 are secured to the plates and sills outside of the side and end posts and diagonal corner braces. Side and end fascia boards, 26, 27, which are nailed to the side plate and end plate respectively, cover the upper ends of the sheathing 70 boards. The roof sheathing 28 is supported on the side and end plates, and on carlines 29 and a ridge pole 30 carried thereby.

A wood frame car, such as that shown and described herein, shrinks and warps from 75 changes in climatic conditions, and gets racked to pieces in service. Often the rickety condition of the car frame causes the roof to leak, and thereby permits the lading 80 to become damaged. Moreover, the ends of such a car, even when lined with planking, are not strong enough to resist the battering to which they are not infrequently subjected from shifting lading. In order to strengthen the car end and stiffen the car 85 frame, a rigid end frame or brace, made of vertical Z-bars 31 and horizontal angle plates 32, is secured to the end sill 11 and end plate 17. At their lower ends the Z-bars are bolted to the center sills by means 90 of strap bolts 33, and between their lower and upper ends they are bolted to the end posts 21. The middle truss rods 16 go through the lower ends of the Z-bars and serve to tie them very securely to the car 95 underframe. The Z-bars diverge upwardly from the end sill to the end plate, their upper ends being spaced farther apart than their lower ends, and crossing the upper ends of the diagonal end corner braces 23 100 and being secured thereto and to the end plate. The end posts and the upper ends of the diagonal end corner braces 23, are thereby braced against being thrust outwardly. The Z-bar and angle plate frame is of such 105 shape, and is bolted to the end sill, end posts and end plate in such places, that distortion of the end of the car in its own plane is entirely prevented.

On the inside of the end plate 17 opposite 110 the top angle plate 32 is a stiffener 34, bolted to the frame by through bolts 35. The

- ends of the stiffener are connected to the side plates by diagonal tie rods 36. The tie rods 36 are threaded at the ends which engage the ends of the stiffener, and their opposite ends are provided with eyes which are pivoted to castings 37 which are bolted to the side plates and to the ends of nearest carline 29. Strap tie rods 38 are bolted to the side plates near the castings 37 and extend diagonally down and through the end posts 21. Their lower ends pass through castings 39 on the outside of the car and are provided with nuts which bear against the castings and serve to tighten them up.
- 15 These diagonal side tie rods 38 hold the side plates and end plate together, and keep the side diagonal corner braces 22 tight, thereby stiffening the side of the car, and in connection with the top diagonal tie rods 36,
- 20 stiffening the end plate and the roof.

From the above description it is evident that the metal frame and its connections to the wood framework of the car braces the end of the car, and the end portions of the car sides and roof, against the forces which tend to burst out the end of the car or cause the roof to leak, however they may be applied.

The invention is not restricted to the detail constructions shown and described, nor to cars having wooden framing arranged as shown and described.

What I claim as my invention is as follows:

- 35 1. In combination in a car having side and end plates, corner posts and diagonal side and end corner braces, connections between the side plates and the end plate and inclined ties from the side plates to the corner posts.
- 40 2. In combination in a car having side and end plates, corner posts and diagonal side corner braces, inclined ties from the side plates to the corner posts, and ties from near the ends of the side plates to the end plate.
- 45 3. In combination in a car having side and end plates, corner posts and diagonal side corner braces, a brace from side plate to side plate, inclined ties from the side plates to the corner posts, and diagonal ties from the side plates adjacent to the ends of said inclined ties to the end plate.
- 50 4. In combination in a car having side and end plates, corner posts and diagonal side and end corner braces, a brace from side plate to side plate, inclined ties from the side plates to the corner posts, diagonal ties from the side plates adjacent to the ends of said ties to the end plate, and a rigid frame secured to said end plate and end corner braces and connected to said diagonal ties.
- 55 5. In combination in a car having side and end plates, corner posts and diagonal end corner braces, a brace from side plate to

side plate and diagonal ties from the side plates to the end plate, and a rigid frame secured to said end plate and end corner braces and connected to said diagonal ties at the top and to the car underframe at the bottom.

6. In combination in a car having side and end plates, corner posts and diagonal side corner braces, a truss connection between the side plates and end plate, and adjustable diagonal ties from the side plates to the corner posts.

7. In combination in a car having side and end plates, corner posts and diagonal side and end corner braces, a brace from side plate to side plate, diagonal ties from the side plates to the corner posts, and adjustable ties from the side plates adjacent to the ends of said diagonal ties to the end plate.

8. In combination in a car having side and end plates, end posts and divergent end braces connected to the end plate at their upper ends, a brace from side plate to side plate and diagonal ties from the side plates to the end plate.

9. In combination in a car having side and end plates, end posts and divergent end braces connected to the end plate at their upper ends, a brace from side plate to side plate and diagonal ties from the side plates to the end plate, said ties having their outer ends pivoted to the side plates.

10. In combination in a car having side and end plates, end posts and divergent end braces connected to the end plates at their upper ends, a brace from side plate to side plate and diagonal ties from the side plates to the end plate, said ties being adjustable in length and having their outer ends pivoted to the side plates.

11. A metal frame attachment for a car end brace, said frame having a pair of divergent members adapted to be connected at their ends to the end sill and end plate, and members rigidly connecting said divergent members between their ends.

12. A metal frame attachment for a car end brace, said frame having a pair of divergent members spaced apart at both ends and members rigidly connecting them, the ends of said divergent members which are spaced farther apart being adapted to be connected to an end plate of a car.

13. A metal frame for a car end brace, said frame having a pair of divergent members and members rigidly connecting them, said frame being adapted for bolting on to the end sill, end plate and end posts of a wooden car.

14. In a car end construction, in combination with end posts, end sill and end plate, a pair of diagonal end braces, each of which is secured to said end plate and end sill and crosses one of said end posts.

15. In a car end construction, in combina-

tion with end posts, end sill and end plate, a pair of divergent end braces, each of which is secured to said end plate and end sill, and a cross brace secured to said end braces and 5 to said end posts.

16. In a car end construction, in combination with end posts, end sill and end plate, a pair of divergent end braces, each of which is secured to said end plate and end 10 sill, and a pair of cross braces secured to said end braces above and below the middle points thereof, and each of which cross braces is secured to said end posts.

17. In a car end construction, in combina-

tion with end posts, end sill and end plate, 15 a pair of diagonal end braces, each of which is secured to said end plate and end sill and crosses one of said end posts and is secured thereto, and a cross brace connecting the diagonal braces near their ends and secured 20 to the ends of said end posts.

Signed at New York city, New York, this 30th day of October, 1914.

WALTER P. MURPHY.
